ABSTRACT OF THE DISCLOSURE

Novel compounds useful as hypoglycemic agents are represented by the formula

wherein X represents oxygen or sulfur; A represents a bond, or a straight or branched alkylene chain of from 1 to 3 carbon atoms; R represents hydrogen, a straight or branched lower alkyl group of from 1 to 4 carbon atoms, a straight or branched lower alkenyl group of from 3 to 6 carbon atoms, a cycloalkyl group of from 3 to 6 carbon atoms or phenyl; R¹ represents hydrogen or a straight or branched lower alkyl group of from 1 to 4 carbon atoms; n is an integer of from 3 to 11; and pharmaceutically acceptable acid addition salts and individual optical isomers of the compounds where applicable.

FIELD OF INVENTION

This invention relates to novel lactamimide derivatives useful as hypoglycemic agents and to methods of using the compounds either alone or in the form of pharmaceutical preparations.

SUMMARY OF INVENTION

Lactamimide derivatives of the following Formula I and pharmaceutically acceptable acid addition salts and individual optical isomers where applicable are useful as hypoglycemic agents.

Formula I

In the above Formula I, X represents oxygen or sulfur; A represents a bond or a straight or branched alkylene chain of from 1 to 3 carbon atoms; R represents hydrogen, or a straight or branched lower alkyl group from 1 to 4 carbon atoms, a straight or branched lower alkenyl group of from 3 to 6 carbon atoms, cycloalkyl of from 3 to 6 carbon atoms or phenyl; R¹ represents hydrogen or a straight or branched lower alkyl group of from 1 to 4 carbon atoms; and n is an integer of from 3 to 11. Pharmaceutically acceptable acid addition salts and individual optical isomers of the compounds where applicable are also included within the scope of this invention.

DETAILED DESCRIPTION OF INVENTION

For convenience and uniformity all the compounds of this invention are named and represented as 2-imino-perhydroazacarbocyclics, as represented by general Formula I. It is well known, however, that compounds of this

2

type may also be represented by the tautomeric form illustrated by the following Formula II:

Formula II

This tautomerism has been discussed by R. Kowk and P. Pranc, J. Org. Chem. 32, 740 (1967). The compounds of this invention when represented by Formula II will be named differently than when represented by Formula I. In solution under the conditions of therapeutic utility the proportion of each tautomeric form, or the delocalization of the charge between the two nitrogens, will be dependent upon numerous factors including the nature of the substituents, the pH of the medium, and the like. This equilibrium state is conveniently depicted by the following Formula III.

Formula III

25 In the above Formulas II and III, X, A, R, R¹ and n have the meanings defined hereinbefore.

As examples of straight or branched lower alkyl groups of from 1 to 4 carbon atoms which R and R¹ may represent in the above Formulas I to III there may be mentioned methyl, ethyl, propyl, isopropyl, butyl, *tert*-butyl, and the like.

As examples of alkenyl groups of from 3 to 6 carbon atoms which R may represent in the above Formulas I to III there may be mentioned cyclopropyl, cyclobutyl, cyclopentyl and cyclohexyl.

As examples of alkenyl groups of from 3 to 6 carbon atoms which R may represent in the above Formulas I to III there may be mentioned allyl, 2-butenyl, 3-butenyl, 3-pentenyl, and the like.

40 Pharmaceutically acceptable acid addition salts of the base compounds of this invention are those of any suitable inorganic or organic acids. Suitable inorganic acids are for example, hydrochloric, hydrobromic, sulfuric or phosphoric acids, and the like. Suitable organic acids are, 45 for example, carboxylic acids such as acetic, propionic, glycolic, lactic, pyruvic, malonic, succinic, fumaric, malic, tartaric, citric, ascorbic, maleic, hydroxymaleic, benzoic, hydroxybenzoic, phenylacetic, cinnamic, salicylic, 2-phenoxycbenzoic, and the like, or sulfonic acids such as methane sulfonic, 2-hydroxyethane sulfonic acid and the like.

As examples of compounds of this invention there may be mentioned:

55 2-[α-(2-thienyl)benzyl]imino]azacyclotridecane, hexahydro-2-(2-thienylimino)azepine, hexahydro-2-[1-(2-thienyl)propylimino]azepine,

2-(furfurylimino)hexahydroazepine, 2-[α-(2-furyl)benzyl]imino]octahydroazocine, hexahydro-2-[α-(2-thienyl)benzyl]imino]azepine,

60 2-[1-(2-thienyl)propylimino]pyrrolidine, 2-[α-cyclopropyl-2-thienyl]imino]hexahydroazepine, hexahydro-2-[β-(2-thienyl)isopropylimino]azepine, hexahydro-2-[2-(3-[2-thienyl]butyl)imino]azepine,

65 hexahydro-2-[2-(1-[2-thienyl]pent-4-enyl)imino]azepine,

2-[2-(1-[2-furyl]pent-4-enyl)imino]azacyclododecane, 2-[α-(2-thienyl)benzyl]imino]piperidine,

70 5-*tert*-butylhexahydro-2-[1-(2-thienyl)-2-butylimino]azepine,

2-[α-cyclopropyl-2-thienyl]imino]piperidine, octahydro-2-[α-(2-thienyl)benzyl]azocine,

octahydro-2-[1-(2-thienyl)-2-butylimino]azocine,
2-[α -(α -cyclopropyl-2-thenyl)imino]octahydroazocine,
2-[1-(2-thienyl)-2-butylimino]piperidine,
octahydro-2-[1-(2-thienyl)-2-butylimino]azonine,
2-[α -(2-furyl)benzyl]imino]hexahydroazepine,
2-[α -(2-furyl)benzyl]imino]piperidine,
hexahydro-2-(3-[4-(2-furyl)-4-cyclopentyl]butyl-
imino)azepine,
2-(2-thienylimino)azacycloundecane,
5-n-propylhexahydro-2-(2-[1-(2-furyl)hex-4-enyl]-
imino)azepine,

and the like and pharmaceutically acceptable acid addition salts thereof.

The compounds of this invention are useful as hypoglycemic agents and may be used to control hyperglycemic conditions, such as occur for example in diabetic patients, by inducing a hypoglycemic response in the patient. To illustrate the utility of the compounds of this invention male rats of the Charles River C.D. strain each weighing from 120 to 140 grams were fastened for 15 hours then injected subcutaneously with 1 g./kg. of body weight of glucose in 0.5 ml. of 0.9% sodium chloride solution. Immediately following the glucose injection the animals were administered by oral intubation a compound of this invention in 0.5 ml. of carboxymethyl cellulose. Two hours after the test compound was administered blood was withdrawn from the animals and a quantitative analysis of glucose in the plasma was performed by use of the ultramicro glucose oxidase procedure as described by L. P. Cawley et al., Am. J. Clin. Path. 32, 195-200 (1959).

Animals administered carboxymethyl cellulose with no test compound served as a control. The results of this test are summarized in the following Table I.

TABLE I

Test compound	Dosage, mg./kg.	Percent reduction in plasma glucose from control
Octahydro-2-[1-(2-thienyl)-2-butylimino]azocine hydrochloride	100 12.5	68 31
Hexahydro-2-[2-(1-[2-thienyl]pent-4-enyl)-imino]azepine hydrochloride	100 50	65 49
2-[α -(2-furyl)benzyl]imino]hexahydroazepine hydrochloride	100 50	55 37
Hexahydro-2-[2-(3-[2-thienyl]butyl)imino]azepine hydrochloride	100	46
2-[α -(α -cyclopropyl-2-thenyl)imino]hexahydroazepine hydrochloride	100	44
Hexahydro-2-[α -(2-thienyl)benzyl]imino]azepine hydrochloride	100 50	50 46
2-[α -(2-furyl)benzyl]imino]octahydroazocine hydrochloride	100	51

These novel compounds can be administered to animals, warm blooded animals and particularly mammals, either alone or in the form of pharmaceutical preparations which contain the novel compounds suitable for oral or parenteral administration. Pharmaceutical preparations containing novel compounds of this invention and conventional pharmaceutical carriers can be employed in unit dosage forms such as solids, for example, tablets and capsules, or liquid solutions, suspensions or elixirs for oral administration, or liquid solutions, suspensions, emulsions, and the like for parenteral administration. The quantity of compound administered can vary over a wide range to provide from about 0.1 mg./kg. (milligram per kilogram) to about 100 mg./kg. of body weight of the patient per day to achieve the desired effect. Unit doses of these compounds can contain from about 5 to 500 mg. of the compound and may be administered, for example, from 1 to 4 times daily. Specific Examples 25 to 28 are illustrative of pharmaceutical preparations containing as active ingredients compounds of this invention.

The compounds of this invention may be prepared by reacting an excess of a lactim ether of the formula

with a primary amine of the following formula

in a manner similar to that reported by R. E. Benson and T. L. Cairns in J. Am. Chem. Soc. 70, 2115-8 (1948). The various symbols X, A, R, R¹ and n have the meanings defined hereinbefore. This reaction may be carried out with or without a solvent. When a solvent is employed that preferred is a lower alcohol, such as methanol, ethanol, isopropyl alcohol, butanol and the like. Other solvents, such as, aromatic hydrocarbons, for example, benzene and toluene may also be used as suitable solvents for this reaction. A basic or an acidic catalyst such as a tertiary amine or hydrogen chloride may be added to the reaction mixture. In general it is preferred that the hydrochloride salt of the amine be used in the reaction. The temperature of the reaction varies from -40° C. to 180° C., and the preferred temperature is about 15-25° C. The reaction time varies from 1 hour to about 60 days being dependent upon the temperature of the reaction, the reactant primary amine, and more particularly on the degree of steric hindrance of the amine since highly sterically hindered amines react very slowly.

The lactim ethers as represented by Formula IV which find use in this reaction may be prepared from commercially available corresponding lactams by methods known in the art. For example, by reaction of an appropriate lactam with dimethyl sulfate in a solvent such as benzene, toluene, xylene or the like at the reflux temperature of the solvent for 2-24 hours the corresponding *o*-methyl lactim ether is obtained.

The amines as represented by Formula V which find use in this reaction may be prepared by several methods known to the art. For example, a nitrile of the formula

may be reacted with an alkyl- or phenylmagnesium halide compound followed by reduction of the resulting ketimine complex *in situ* with lithium aluminum hydride. Also, nitriles of the formula

particularly wherein R is a cycloalkyl group of from 3 to 6 carbon atoms, may be reacted with 2-thienylmagnesium halide followed by reduction. In some instances it may be advantageous to prepare the primary amines from compounds of the formula

via Hoffman or Curtius degradation, such as described by F. J. McCarty et al., J. Med. Chem. 11, 534 (1968), or as described by Van Zoeren in U.S. 2,367,702.

The compounds of this invention may also be prepared using a complex of an appropriate lactam of the formula

wherein n and R¹ have the meaning defined above, with phosphorus oxychloride, phosgene, borontrifluoride ether-

ate, dimethylsulfate, hydrogen halide or a combination of two or more such reagents. Several attempts have been made to formulate the structure of these complexes, and one formulation includes the imino halide, that is, 2-chloro-4,5,6,7-tetrahydro-3H-azepine. However, none of the formulations have been unambiguously established. This reaction has been studied by H. Bredereck in a series of articles in *Chem. Ber.*, 1953-1968, particularly in vol. 94, 2278 (1961) and vol. 97, 1403 (1964). The complex formed is reacted with an appropriate primary amine described hereinabove in an aromatic hydrocarbon solvent such as benzene, toluene or xylene or an alkyl polyhalide solvent such as carbon tetrachloride, chloroform, methylene chloride, dichloroethane, tetrachloroethylene or the like. The reaction temperature is limited by the boiling point of the solvent, however, in some cases it is advantageous to carry out the reaction at room temperature or with cooling at 0 to -40° C. depending on the reactants.

Similarly the above reaction may be carried out by using known thiolactim ethers such as S-methylthioprocaprolactim [H. Behringer and H. Meier, *Ann.* 607, 73-91 (1957)], or by using thiolactams wherein the latter case it may be advantageous to employ a catalyst such as mercury or silver oxide or cyanide [J. Gautier and J. Renault, *C. R. Acad. Sci.* 234, (1952)].

Also by catalytic hydrogenation of an appropriate amino-pyridine derivative as described by T. Grave, *J. Am. Chem. Soc.* 46, 1460 (1924), M. Friesfelder et al., *J. Org. Chem.* 29, 3730 (1964) and L. Birkhofer, *Ber.* 75, 429 (1942), compounds of this invention containing a pentamethyleneimine moiety may be obtained.

The following specific examples are illustrative of the invention.

EXAMPLE 1

2-[[α -(2-thienyl)benzyl]imino]azacyclotridecane hydrochloride

To 6.4 g. (0.033 mole) of 2-azacyclotridecanone in 100 ml. of benzene is added 4.8 g. (0.031 mole) of phosphorus oxychloride. The mixture is stirred at room temperature for 4 hours after which 6.5 g. (0.029 mole) of

tallized and recrystallized from isopropyl alcohol-water to give 2-[[α -(2-thienyl)benzyl]imino]azacyclotridecane hydrochloride, M.P. 150-160° C. (dec.).

EXAMPLE 2

Hexahydro-2-(2-thenylimino)azepine hydrochloride

A solution of 11.2 g. (0.0995 mole) of 2-thenylamine in 700 ml. of ether is acidified with ethereal hydrochloric acid after which the precipitate is collected and dried to give 2-thenylamine hydrochloride.

A mixture of 15.1 g. (0.101 mole) of the above obtained 2-thenylamine hydrochloride, 15 ml. of o-methylcaprolactim and 5 ml. of ethanol is stirred with cooling under tap water until the exothermic reaction is complete.

The mixture is allowed to stand at room temperature for about 4 hours with occasional stirring and the addition of sufficient ethanol to prevent the mixture from solidifying. The mixture is then cooled to -20° C. after which the precipitate is collected, recrystallized from acetone-methanol and dried to give hexahydro-2-(2-thenylimino)

azepine hydrochloride, M.P. 207-209° C. (dec.).

EXAMPLE 3

Hexahydro-2-[1-(2-thenyl)propylamino]azepine hydrochloride

A mixture of 12 g. (0.0625 mole) of 1-(2-thenyl)-1-propylamine hydrochloride and about 15 ml. of o-methylcaprolactim is allowed to stand at room temperature for 8 days with occasional stirring and the addition of sufficient absolute ethanol to prevent solidification of the mixture. The mixture is cooled to -20° C., then the precipitate is collected, washed with ether, air dried and recrystallized from acetone-methanol to give hexahydro-

2-[1-(2-thenyl)propylamino]azepine hydrochloride, M.P. 187-187.5° C.

Following the general procedure of Example 3 only substituting for 1-(2-thenyl)-1-propylamine hydrochloride and o-methylcaprolactim respectively the amine hydrochloride and lactim ether listed in the following Table II the respective compounds as listed are obtained.

TABLE II

Ex. No.	Compound name, M.P., ° C.	Amine, HCl	Lactim, ether	Reaction time, days
4	2-[[α -(2-furyl)benzyl]imino]octahydroazocine hydrochloride, 255-256 (dec.)	α -(2-furyl)benzylamine	o-Methylenantholactim	7
5	Hexahydro-2-[[α -(2-thienyl)benzyl]imino]azepine hydrochloride, 255-256 (dec.)	α -(2-thienyl)benzylamine	o-Methylcaprolactim	7
6	2-1-(2-thenyl)propylimino]pyrrolidine hydrochloride, 109-111 (dec.)	1-(2-thenyl)-2-butylamine	o-Methylbutyrolactim	29
7	2-[(α -cyclopropyl-2-thenyl)imino]hexahydroazepine hydrochloride, 207-209	α -Cyclopropyl-2-thenylamine	o-Methylcaprolactim	7
8	Hexahydro-2-[β -(2-thienylisopropylimino]azepine hydrochloride, 177.5-180	β -(2-thienyl)isopropylamine	do	3
9	Hexahydro-2-[2-(3-[2-thienyl]butyl)imino]azepine hydrochloride, 188-193	3-(2-thienyl)butylamine	do	6
10	Hexahydro-2-[2-(1-[2-thienyl]pent-4-enyl)imino]azepine hydrochloride, 143-146	2-[1-(2-thienyl)pent-4-enyl]amine	do	7
11	2-[(α -[2-thienyl]benzyl)imino]piperidine hydrochloride, 198-200	α -(2-thienyl)benzylamine	o-Methylvalerolactim	8
12	5- <i>tert</i> -butylhexahydro-2-[1-(2-thienyl)-2-butylimino]azepine hydrochloride, 223-226	[1-(2-thienyl)-2-butylamine	o-Methyl-5-(<i>tert</i> -butyl)-caprolactim	8
13	2-[(α -cyclopropyl-2-thenyl)imino]piperidine hydrochloride, 172-174	α -Cyclopropyl-2-thenylamine	o-Methylvalerolactim	12
14	Octahydro-2-[(α -[2-thienyl]benzyl)imino]azocine hydrochloride, 280-281	α -(2-thienyl)benzylamine	o-Methylenantholactim	8
15	Octahydro-2-[1-(2-thienyl)-2-butylimino]azocine hydrochloride, 188-190	1-(2-thienyl)-2-butylamine	do	10
16	2-[(α -cyclopropyl-2-thenyl)imino]octahydroazocine hydrochloride, 202-204	α -Cyclopropyl-2-thenylamine	do	21
17	2-[1-(2-thienyl)-2-butylimino]piperidine hydrochloride, 134-136	1-(2-thienyl)-2-butylamine	o-Methylvalerolactim	13
18	Octahydro-2-[1-(2-thienyl)-2-butylimino]azonine hydrochloride, 173-175	do	o-Methylcapryllactim	12
19	2-[(α -[2-furyl]benzyl)imino]hexahydroazepine hydrochloride 216-218	α -(2-furyl)benzylamine	o-Methylcaprolactim	4
20	2-[(α -[2-furyl]benzyl)imino]piperidine hydrochloride, 169-171	α -(2-furyl)benzylamine	o-Methylvalerolactim	8

α -(2-thienyl)benzylamine hydrochloride is added. Stirring is continued at room temperature for 1 hour then at reflux temperature for 4 hours. The resulting solution is allowed to cool to room temperature and stand over night after which it is washed with 2 N hydrochloric acid. The organic layer is separated and washed with a saturated sodium chloride solution and dried over sodium sulfate. The solvent is evaporated, and the resulting oil is crys-

EXAMPLE 21

2-(furylimino)hexahydroazepine hydrochloride

A solution of 17.8 g. (0.183 mole) of furfurylamine in 700 ml. of ether is acidified with ethereal hydrochloric acid after which the precipitate is collected and dried to give furfurylamine hydrochloride, M.P. 138.5-140° C.

A mixture of the above obtained furfurylamine hydrochloride and 30 ml. of o-methylcaprolactim is allowed to

stand at room temperature for 2 days with occasional stirring and the addition of sufficient ethanol to prevent the mixture from solidifying. The mixture is then cooled to -20° C. then the precipitate collected and recrystallized from methanol-acetone to give 2-(furfurylimino)hexahydroazepine hydrochloride, M.P. 149.5-150.5° C.

EXAMPLE 22

2-(furfurylimino)azacycloundecane hydrochloride

Following the procedure of Example 1 only substituting for 2-azacyclotridecanone and α -(2-thienyl)benzylamine hydrochloride appropriate amounts of 2-azacycloundecanone and furfurylamine hydrochloride respectively, 2-(furfurylimino)azacycloundecane hydrochloride is obtained.

EXAMPLE 23

 α -Methylvalerolactim

To a refluxing solution of 100 g. (1.01 moles) of valerolactim in 350 ml. of dry benzene is added dropwise 125 g. (0.99 mole) of dimethyl sulfate. After refluxing overnight the mixture is treated with saturated potassium carbonate solution, dried and the solvent is evaporated. The product is distilled at 20 mm., B.P. 55-57° C.

EXAMPLE 24

Following the procedure of Example 22 only substituting for valerolactam, the appropriate molar equivalent amount of butyrolactam, caprolactam, enantholactam, caprylactam, and 5-*tert*-butylcaprolactam the following respective compounds are obtained.

α -methylbutyrolactim, B.P. 65-67° C. (100 mm.), α -methylcaprolactim, B.P. 60-65° C. (13.0 mm.), α -methyleneantholactim, B.P. 48-53° C. (2.0 mm.), α -methylcaprylactim, B.P. 44-46° C. (0.5 mm.), α -methyl-5-*tert*-butylcaprolactim, B.P. 76-79° C. (0.4-2.3 mm.).

EXAMPLE 25

An illustrative composition for tablets is as follows:

	Per tablet, mg.
(a) Octahydro - 2 - [1 - (2 - thienyl) - 2 - butyl-imino]azonine hydrochloride	100
(b) Wheat starch	15
(c) Lactose	33.5
(b) Sodium chloride, q.s.	

A granulation obtained upon mixing lactose with the starch and granulated starch paste is dried, screened and mixed with the active ingredient (a) and magnesium stearate. The mixture is compressed in tablets weighing 150 mg. each.

EXAMPLE 26

An illustrative composition for hard gelatin capsules is as follows:

	Per capsule, mg.
(a) Hexahydro - 2 - [2 - (1 - [2 - thienyl] - pent-4-enyl)imino]azepine hydrochloride	150
(b) Talc	25

The formulation is prepared by passing the dry powders of (a) and (b) through a fine mesh screen and mixing them well. The powder is then filled into No. 0 hard gelatin capsules at a net fill of 175 mg. per capsule.

EXAMPLE 27

An illustrative composition for pills is as follows:

	Per pill, mg.
(a) 2 - [[α - (2 - furyl)benzyl]imino] - octahydro-azocene hydrochloride	150
(b) Corn starch	120
(c) Liquid glucose	15

The pills are prepared by blending the active ingredient and starch then adding the liquid glucose with thorough

kneading to form a plastic mass. The pills are then cut and formed from the plastic pill mass.

EXAMPLE 28

5 An illustrative composition for a parenteral injection is the following wherein the quantities are on a weight to volume basis.

- (a) 2 - [(α - cyclopropyl - 2 - phenyl)imino] - hexahydroazepine hydrochloride _____ mg. 100
 (b) Sodium chloride, q.s.
 (c) Water for injection to make _____ ml. 10

10 The composition is prepared by dissolving the active ingredient and sufficient sodium chloride in water for injection to render the solution isotonic. The composition may be dispensed in a single ampule containing 100 mg. of the active ingredient for multiple dosage or in 10 ampules for a single dosage.

15 What is claimed is:

1. A compound selected from a base of the formula

20 25 wherein X is selected from oxygen or sulfur; A is selected from the group representing a bond or a straight or branched alkylene chain of from 1 to 3 carbon atoms; R is selected from the group consisting of hydrogen or a straight or branched lower alkyl group of from 1 to 4 carbon atoms, a straight or branched lower alkenyl group of from 3 to 6 carbon atoms and phenyl; R¹ is selected from the group consisting of hydrogen or a straight or branched lower alkyl group of from 1 to 4 carbon atoms; n is an integer of from 3 to 11; and pharmaceutically acceptable acid addition salts thereof.

- 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760
2. A compound of claim 1 wherein X is oxygen.
3. A compound of claim 2 which is 2-[(α -[2-furyl]-benzyl)imino]hexahydroazepine and pharmaceutically acceptable acid addition salts thereof.
4. A compound of claim 2 which is 2-[[(α -[2-furyl]-benzyl)imino]octahydroazocene and pharmaceutically acceptable acid addition salts thereof.
5. A compound of claim 1 wherein X is sulfur.
6. A compound of claim 5 which is octahydro-2-[1-(2-thienyl) - 2 - butylimino]azonine and pharmaceutically acceptable acid addition salts thereof.
7. A compound of claim 5 which is hexahydro-2-[2-(1-[2-thienyl]pent - 4 - enyl)imino]azepine and pharmaceutically acceptable acid addition salts thereof.
8. A compound of claim 5 which is hexahydro-2-[[(α -[2-thienyl]benzyl)imino]azepine and pharmaceutically acceptable acid addition salts thereof.
9. A compound of claim 5 which is 2-[α -cyclopropyl-2-thienyl)imino]hexahydroazepine and pharmaceutically acceptable acid addition salts thereof.
